V. E. KIRK

HAIR HOLDER

Filed Nov. 9, 1922

FIG. 1

FIG. 3

FIG. 2

FIG. 4

VOLNEY E. KIRK
INVENTOR.

BY

R. W. Smith
ATTORNEY.

UNITED STATES PATENT OFFICE.

VOLNEY E. KIRK, OF LOS ANGELES, CALIFORNIA.

HAIR HOLDER.

Application filed November 9, 1922. Serial No. 599,938.

To all whom it may concern:

Be it known that I, VOLNEY E. KIRK, a citizen of the United States, residing at Los Angeles, county of Los Angeles, State of California, have invented new and useful Improvements in Hair Holders, of which the following is a specification.

This invention relates to hair holders particularly adaptable for use in motoring, swimming, or otherwise exercising, and it is the object of the invention to provide hair retaining means which may be readily adjusted with relation to the head, in order to engage the hair at any desired point.

More particularly the invention includes a brow encircling band and a band extending over the head, with connections between said bands whereby the position of the head band may be adjusted with relation to the brow band, and both of said bands may be adjusted in length.

It is a further object of the invention to provide hair holding means adapted to lie across the head in spaced relation longitudinally of the head, for insuring positive retaining of the hair in position, said holding means having a spacer associated therewith for maintaining proper spaced relation between said holding means.

It is a still further object of the invention to provide hair holding means of sufficient width and so positioned as to overlie a relatively large portion of the hair, such a construction being of particular utility in swimming or when otherwise violently exercising.

The invention also contemplates the provision of a hair holder for normal use having a brow band and a head band, with a readily detachable head piece adapted to be connected to the hair holder, and used when so desired, for covering the hair.

The invention will be readily understood from the following description of the accompanying drawings, in which:

Fig. 1 shows the device in position for use upon the head.

Fig. 2 is a fragmentary vertical section through the front of the hair holder.

Fig. 3 is a detail section on the line 3—3 of Fig. 1.

Fig. 4 is a plan view of a hair holder showing a modified construction.

The hair holder includes a brow encircling band 1 which may be a strip of rela-

tively narrow water-proof fabric, or other suitable pliable material. The brow band is received around the head across the top of the brow and above the ears, and the ends of the strip forming said band preferably overlap at one side of the head to provide for adjusting the size of the brow band as will be described.

A second band 2, preferably of the same material, is connected at its ends to the sides of the brow band, and is adapted to extend transversely over the head so as to engage the hair for retaining the same in place.

The connections between bands 1 and 2 provide for adjusting the length of the respective bands, and also for pivotally adjusting band 2 with relation to band 1, and for adjusting the head band along the brow band longitudinally of the head.

As a consequence the band 2 may be so positioned as to overlie the ends of the front hair for retaining the same in place, irrespective of the length of said hair.

The connection at each side of the device consists of a member 3 having slots 4 with the band 1 received through said slots so that said members may be adjusted along the sides of the brow band. At one side of the brow band, both ends of the strip forming the same are received through the slots of member 3, in order that the length of the brow band may be conveniently adjusted.

Members 5 are pivoted to the members 3 as shown at 6, the members 5 having slots 7 adapted to have the ends of band 2 received therethrough. By this arrangement it will be seen that the length of band 2 may be readily adjusted, and that a combined pivotal and slidable connection is formed between the head band and the brow band.

The ends of band 2 preferably extend downwardly so as to overlie the inner sides of members 3 as shown in Fig. 3, thereby protecting the sides of the head from the connecting means.

In the modification of the invention illustrated in Fig. 4, the head band is shown as a double strip construction having the strips spaced longitudinally of the head to provide additional means for retaining the hair in place. As an instance of this arrangement, strips 2a spaced longitudinally of the

head are connected at their ends to form end tabs 2^b received through the slots in members 5 as previously described.

The strips 2^a may be retained in proper spaced relation by a spacer connecting the same and extending lengthwise of the head. This spacer is shown as a strip 10, sufficiently flexible to conform to the contour of the head while being of a suitable stiffness 10 to maintain strips 2^a in spaced relation, and fastened at its ends to strips 2^a in any suitable manner as shown at 11.

When swimming or engaged in other violent exercise, it will sometimes be found desirable to have hair holding means which will cover the entire head or a substantial portion thereof. For this purpose a suitable piece of material may be connected to a hair holder so as to overlie the hair.

20 In the present instance, such a head covering is shown in Fig. 1, adapted to retain the front hair in position by overlying all of the same, said cover being supported between the brow band and the head band 25 by detachable fastening means, so that it may be readily removed or placed in position.

This detachable head covering consists of a piece of material 15, of the required shape, 30 and adapted to conform to the contour of the head. Tabs 16 having separable fasteners shown as heads and sockets 17-18, are provided at the edges of the piece of material, and said tabs are adapted to be 35 looped around bands 1 and 2 and the fasteners then engaged, for retaining the head cover in position.

It will be noted that after cover 15 has 40 been connected to the hair holder, it may be drawn down tight upon the hair by swinging band 2 rearwardly as far as possible.

It will be apparent that various changes 45 may be made in the construction, combination, and arrangement of parts as thus described without departing from the spirit of the invention.

What is claimed is:

1. A hair holder including a brow encircling band, a band connected to said brow band and adapted to extend over the head, and a cover for the hair having loops adapted 50 to receive said brow band and said head band through the same for detachably fixing said cover between said bands.

2. A hair holder comprising a brow encircling band, a band connected to opposite sides of said brow band and adapted to extend over the head, and material between 60 said brow encircling band and said head band and connected thereto, said connections between said brow band and said head band providing for adjustment of the latter relative to said brow band and longitudinally 85 of the head for stretching said material.

3. A hair holder comprising supporting means, a member adapted to extend over the head, material between said supporting means and said member, detachable connections between said material and said supporting means and said member, and a connection between said supporting means and said member providing for adjustment of said member relative to said supporting means and longitudinally of the head 75 for stretching said material.

4. A hair holder comprising a brow encircling band, a member adapted to extend over the head, and connection between said member and said brow band providing for 80 sliding adjustment of said head member along said brow band, and for adjustment of the length of said head member and said brow band.

5. A hair holder comprising a brow encircling band, a member adapted to extend over the head, and pivoted connections secured to the respective ends of said head member and slidable along opposite sides of 90 said brow band.

6. A hair holder comprising a strip forming a brow encircling band, members slidably mounted on opposite sides of said brow band with the ends of said brow strip received through one of said members for adjusting the length of said brow band, members pivoted to said slidable members, and a band adapted to extend over the head having its ends slidably engaged by said pivoted members for adjusting the length of said 100 head band.

7. A hair holder comprising a brow encircling band, a band adapted to extend over the head, pivoted connections between the ends of said head band and opposite sides of 105 said brow band adapted for angular adjustment of said head band relative to said brow band, and for sliding adjustment of said head band along said brow band, a piece of material between said head band and 110 said brow band, and detachable connecting means between said material and said bands.

8. A hair holder comprising a brow encircling band, members slidably mounted on opposite sides of said brow band, and a 115 band adapted to extend transversely over the head having its ends connected to said members for sliding adjustment of said head band longitudinally of the head.

9. A hair holder comprising a brow encircling band, members secured to opposite sides of said brow band, members pivoted to said first members, and a band adapted to extend over the top of the head having its ends adjustably engaged by said pivoted 125 members.

10. A hair holder comprising a brow encircling band, members slidably mounted on opposite sides of said brow band with the ends of said brow band received through one 130

of said members for adjusting the length of said band, and a band adapted to extend over the head having its ends connected to said members.

5 11. The combination with a hair holder having a brow encircling band and a band connected thereto and adapted to extend over the head, of a waterproof, non-perforate

cover for the hair of the head between said brow band and said head band and having means for detachably connecting the same to said bands. 10

In testimony whereof I have signed my name to this specification.

VOLNEY E. KIRK.
